Primary Examiner — Clare E Heflin(74) *Attorney, Agent, or Firm* — Myron Greenspan;
Lackenbach Siegel, LLP(57) **CLAIM**

I claim the ornamental design for a pendant light fixture, as shown and described.

DESCRIPTION

FIG. 1 is a perspective view of a pendant light fixture showing my new design;

FIG. 2. is a top plan view thereof;

FIG. 3. is a right side elevational view thereof, the left side elevational view being identical to the right side elevational view;

FIG. 4 is a front elevational view thereof, the rear elevational view being identical to the front elevational, view; and,

FIG. 5 is a bottom plan view thereof.
The broken lines shown on the drawings depict portions of the pendant light fixture that form no part of the claimed design.

My suspended pendant light fixture design is characterized by a unique shape as shown, made from metal sheet formed into conical shades which enclose two lamps and lamp-holders in a symmetrical fashion. The luminaire hangs from a central metal pipe that connects the two halves of the fixture.
